GARMENT CADDY

Val W. Washburn, 28359 Aline,
Warren, Mich. 48093

Filed Oct. 16, 1975, Ser. No. 622,995

Term of patent 14 years

Int. Cl. D8—08

U.S. Cl. D8—257

FIG. 1 is a view in perspective of a garment caddy embodying my new design;

FIG. 2 is a front elevational view of a garment caddy shown in FIG. 1;

FIG. 3 is a side elevational view of a garment caddy taken on the line 3—3 of FIG. 2; and

FIG. 4 is a top plan view of a garment caddy taken on the line 4—4 of FIG. 3.

I claim:

The ornamental design for a garment caddy, substantially as shown and described.
